CLAIM

The ornamental design for a hang chair and ottoman, as shown and described.

DESCRIPTION

FIG. 1 is a perspective view of the hang chair and ottoman; FIG. 2 is a perspective view of the hang chair shown separately for ease of illustration;

FIG. 3 is a front view of the hang chair;

FIG. 4 is a left side view of the hang chair, the right side view being a mirror image thereof;

FIG. 5 is a rear view of the hang chair;

FIG. 6 is a top plan view of the hang chair;

FIG. 7 is a bottom plan view of the hang chair;

FIG. 8 is a perspective view of the ottoman shown separately for ease of illustration;

FIG. 9 is a front view of the ottoman;

FIG. 10 is a left side view of the ottoman, the right side view being a mirror image thereof;

FIG. 11 is a rear view of the ottoman;

FIG. 12 is a top plan view of the ottoman; and,

FIG. 13 is a bottom plan view of the ottoman.
